United States Patent Office.

JOHN CLARKE, OF BOSTON, MASSACHUSETTS.

Design No. 3,827, dated February 1, 1870.

DESIGN FOR A STOOL-PAN AND ITS COVER.

The Schedule referred to in these Letters Patent and making part of the same.

To all persons to whom these presents may come:

Be it known that I, JOHN CLARKE, of Boston, of the State of Massachusetts, have made a new ornamental and useful Design for a Stool-Pan and its Cover; and do hereby declare the same to be represented in the accompanying drawings, and thus described:

Of such drawings—

Figure 1 is a side elevation, and

Figure 2, a vertical section of it and its cover.

The body of the pan, shown at A, is in the form of a hollow conic frustum, open at top and closed at bottom.

Projecting from and around the top part of the body is a circular flange, B, flat on top, and having its bottom a *cyma-reversa* in transverse section.

Two concentric grooves, *a b*, are made in and around the entire top of the flange, to receive corresponding annular projections, *c d*, extending from the lower part of the cover C, the form of such cover being as represented.

At the central part of the cover is a projecting knob, *e*.

I claim the design for the stool-pan and cover, as represented and described.

JOHN CLARKE.
